UNITED STATES PATENT OFFICE

120,137

DESIGN FOR A MECHANICAL PENCIL

Lucifer J. Most, Arlington, N. J.

Application February 10, 1940, Serial No. 90,177

Term of patent 7 years

To all whom it may concern:

Be it known that I, Lucifer J. Most, a citizen of the United States, residing at 137 Seeley Avenue, in the county of Hudson, town of Arlington, State of New Jersey, have invented a new, original, and ornamental Design for a Mechanical Pencil, of which the following is a specification, reference being had to the accompanying drawing forming part thereof.

Figure 1 is an elevation of the pencil showing my new design.

Figure 2 is a similar elevational view when the pencil is turned to an angle of 60 degrees to the disclosure in Figure 1, the tip of the pencil being broken away for convenience of illustration.

Figure 3 is a top end view of the pencil.

I claim:

The ornamental design for a mechanical pencil, as shown and described.

LUCIFER J. MOST.
